C. J. LEDWIDGE

VAULT HANDLE

Filed March 27, 1926

FIG. 1.

FIG. 2.

FIG. 3.

Inventor:

C. J. Ledwidge,
By Monroe C. Miller
Attorney.

UNITED STATES PATENT OFFICE.

CHRISTOPHER J. LEDWIDGE, OF HOT SPRINGS NATIONAL PARK, ARKANSAS.

VAULT HANDLE.

Application filed March 27, 1926. Serial No. 97,969.

The present invention relates to grave vault or casket handles, and aims to provide novel means for connecting a handle to the hood of a vault or casket and making provision for the engagement of coupling means employed for securing the hood and bottom of the vault or casket together, with said handle free and unencumbered so that it may be used conveniently in lifting or carrying the vault; said provision also accommodating the strap or equivalent member of the equipment used for lowering the vault into the grave so that the handle is left free to hang down in pendent position without catching against the wall of the grave.

Another object of the invention is the provision of novel means for coupling the hood and bottom of the vault together in combination with the handles of the bottom and hood, with the hood handle free and unencumbered. According to the prevailing practice the handles of the bottom and hood are connected directly by coupling members or devices during shipment of the vault, to hold the hood and bottom assembled, but this is objectionable in view of the fact that the handles of the hood are held down by the coupling means and are encumbered so that they may not be conveniently used for lifting or carrying the vault. With the present arrangement the handles of the hood are left free and unencumbered when the coupling means or devices are used, so that the hood handles may be used conveniently for lifting or carrying the vault.

Another object is to provide in combination with the handle of the vault bottom, a caster, in order that the vault may be conveniently moved about on the floor or other surface such as during transportation.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Figure 1 is a side elevation of the improved handles with the coupling member applied.

Fig. 2 is a vertical section on the line 2—2 of Fig. 1.

55

Fig. 3 is a rear or inside view of the hood handle and its attaching means when removed from the hood.

The handles are used on an air seal grave vault or casket comprising a bottom 7 and a hood 8, said hood using the diving bell principle to exclude water from the vault, as well known. The handles are provided at suitable points at the sides and ends of the vault as usual, and only a single pair of handles is shown and described herein.

A plate 9 is welded, bolted or otherwise secured to the lower surface of the vault bottom 7 at one edge thereof and has upwardly extending arms 10 projecting across said edge of the bottom, and a horizontal handle or handle bar 11 is united with the upper ends of the arms 10 for convenience in lifting or carrying the bottom of the vault when the hood 8 is removed therefrom.

75

A companion handle or handle bar 12 is disposed above the handle 11, and is united with the arms 13 that are fastened to a horizontal hinge rod 14. The rod 14 is seated in the notches or seats 15 of attaching plates 16 that are secured to the wall of the hood 8 above the handle 11, and said plates 16 have slots 17 receiving the arms 13 to permit the handle 12 to be swung down to pendent position or to be swung outwardly and upwardly to lifting or carrying position with the arms 13 projecting outwardly from the hood. The plates 16 have apertures 18 to receive studs 19 welded or otherwise secured to the outer surface of the wall of the hood 8, and cap nuts 20 are screw-threaded on the protruding terminals of said studs to clamp the plates 16 against the wall of the hood.

80

85

90

95

100

With the exception that the hinge rod 14 projects across the space between the plates 16, the structure described up to this point is substantially the same as that in prevailing use on vaults or caskets of the kind described. By having the rod 14 extend across the space between the plates 16 said rod may be used for the engagement of a strap or equivalent element of the equipment used for lowering the vault into the grave. This will leave the handle 12 free so that it may hang down in pendent position, thereby avoiding the possibility of the handle 12 striking or

105

catching against the wall of the grave when the vault is being lowered. The rod 14 also affords means for the engagement of the coupling member or device 21 that will be described presently.

In order to couple the bottom and hood of the vault together during shipment, the coupling member or device 21 is provided, same consisting in a bar or strip of metal 10 having its lower terminal formed into a stem 22 to be inserted downwardly through an aperture 23 in the handle 11, and the stem is screw-threaded to receive a nut 24 thereon. The upper end of the coupling member 21 is 15 formed with a hook 25 to engage over the rod 14 behind the handle 12. Thus, by inserting the stem 22 down through the aperture 23 and engaging the hook 25 over the rod 14, the nut 24 being screw-threaded on 20 the stem 22 will draw the member 21 downwardly, thereby clamping the hood 8 on the bottom 7. This will hold the hood and bottom of the vault assembled during transportation, and the handle 12 is free and unencumbered in order that it may be swung 25 outwardly for carrying or lifting the vault. The coupling member or device 21 is only used for holding the bottom and hood assembled during transportation of the vault prior 30 to the final sealing of the vault, and the coupling member 21 is removed when the vault is opened. The bottom 7 of the vault is lowered into the grave, and the coffin is placed thereon, after which the hood 8 is lowered over the coffin. As hereinbefore indicated the rod 14 is used for the engagement of the strap or member used for lowering the hood, so that the handle 12 will be free to 35 hang down. When the hood is placed over 40 the coffin on the bottom 7 the hood and bottom are locked together by automatic locks (not shown) so as to fasten the hood and bottom together permanently. It is also possible to secure the hood and bottom together 45 before lowering the vault into the grave.

A caster is combined with the handle plate 9. Thus, said plate has an opening 26 in which a caster ball 27 is disposed, with the lower portion of the ball projecting out of said opening below the plate 9. The lower portion of the opening 26 is contracted so as to prevent the ball from dropping out of the opening 26. Anti-frictional balls 28 are disposed between the ball 27 and bottom 7 of 50 the vault, and work against the wall of the opening 26 at the upper edge of said opening. Said balls 28 enable the casterball 27 to rotate freely. The caster ball 27 will enable the vault or casket to be readily moved 55 about on the floor or other surface during transportation when the vault is used as a shipping case. During shipment, when using a coupling member or device 21 for each pair of handles, the handles 12 will be

free for conveniently carrying or lifting the 65 vault or case, and the casters will also facilitate handling by railroad employees and others.

Having thus described the invention, what is claimed as new is:

1. A device of the character described comprising a pair of spaced plates adapted to be secured to the hood of a vault and having slots, a hinge rod engaging and held by said plates and extending across the space between said plates, an upper handle connected to said rod for swinging movement and engaging in said slots, a lower handle for the bottom of the vault, and means to connect the lower handle and said rod between said plates for holding said rod and lower handle against separation with the upper handle free for swinging movement.

2. A device of the character described comprising a pair of spaced plates adapted to be secured to the hood of a vault and having slots, a hinge rod engaging and held by said plates and extending across the space between said plates, an upper handle connected to said rod for swinging movement and engaging in said slots, a lower handle for the bottom of the vault, and means adjustably connected with the lower handle and having a portion to engage over said rod between said plates for holding said rod and lower handle against separation with the upper handle free for swinging movement.

3. A device of the character described comprising an upper handle, a hinge mounting for the upper handle including a hinge 100 rod, a lower handle, and means for connecting said rod and lower handle and leaving the upper handle free for swinging movement.

4. A device of the character described comprising an upper handle, a hinge mounting for said handle including a hinge rod, a lower handle, and a coupling having a hook to engage over said rod and having adjustable means to engage the lower handle 105 for moving said rod and lower handle toward one another, the upper handle being free to swing relatively to said member.

5. A device of the character described comprising a pair of spaced plates adapted to be secured to the hood of a vault, a hinge rod engaging and held by said plates and extending across the space between them, an upper handle connected to said rod for swinging movement, a lower handle, and coupling means to connect said rod and lower handle for moving them toward one another and leaving the upper handle free for swinging movement.

In testimony whereof I hereunto affix my 125 signature.

CHRISTOPHER J. LEDWIDGE.
